(57) **CLAIM**

The ornamental design for a catheter and connector securement device, as shown and described.

DESCRIPTION

FIG. 1 is a perspective view of the catheter and connector securement device shown in an open position;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof; and,

FIG. 7 is a front elevation view thereof.

The broken line showing of parts of the drawings is included for the purpose of illustrating use and environment and forms no part of the claimed design.

1 Claim, 4 Drawing Sheets
